UNITED STATES PATENT OFFICE.

ABRAHAM J. SCHULTZ, OF NEWARK, NEW JERSEY, ASSIGNOR TO COLONIAL STAMPING COMPANY, INC., A CORPORATION OF NEW JERSEY.

DESIGN FOR A CAP FOR POSTS.

58,509.

Specification for Design.

Patented July 26, 1921.

Application filed February 21, 1920. Serial No. 360,397. Term of patent 3½ years.

To all whom it may concern:

Be it known that I, ABRAHAM J. SCHULTZ, a citizen of the United States, residing at Newark, in the county of Essex and State of New Jersey, have invented a new, original, and ornamental Design for a Cap for Posts, of which the following is a specification, reference being had to the accompanying drawing, forming part thereof.

The invention is clearly illustrated in the accompanying drawing, which shows in side elevation my new, original, and ornamental design for a cap for posts.

I claim:

The ornamental design for a cap for posts as shown.

ABRAHAM J. SCHULTZ.
